ALBERT HALLOWELL, OF LOWELL, MASSACHUSETTS.

Letters Patent No. 75,631; dated March 17, 1868.

APPARATUS FOR HEATING FLAT-IRONS.

The Schedule referred to in these Letters Patent and making part of the same.

TO ALL PERSONS TO WHOM THESE PRESENTS MAY COME:

Be it known that I, ALBERT HALLOWELL, of Lowell, in the county of Middlesex, and State of Massachusetts, have invented a new and useful Apparatus for Heating Flat-Irons, &c.; and I do hereby declare the same to be fully described in the following specification, and represented in the accompanying drawings, of which—

Figure 1 is a top view,

Figure 2 a front elevation, and

Figure 3 a longitudinal section of it.

In such drawings, A denotes a stand for sustaining the flat-iron, or article to be heated. This stand is supported over a gas-burner, B, which, in turn, is upheld by a foot or stand, C. A pipe, D, attached to the stand C, serves, when connected with a common gas-burner or tube by a flexible conduit or hose, to supply combustible gas to the burner. The gas is led directly into a small chamber, b, made in the lower part of the burner, and provided with a discharge-opening, c', and a conical valve-seat, c, at its upper part. Within the said seat is a valve, d, applied to the lower end of the stem or wire e, extending through a chamber, f, made axially in the burner. The valve-rod is supported by a spring, g', arranged within the chamber f. Surrounding the chamber f is a series of vertical passages, g g, &c., each of which is open at top. Each of these passages has an air-passage, h, leading into it, and communicates with the chamber f by a small hole, i. A deflector, k, is screwed into the top of the chamber f, and extends over the mouths of discharge of the several passages g g, the valve-stem being passed concentrically through the deflector. By such mode of applying the deflector to the chamber f, it not only forms a stopper to the top thereof, but can be adjusted vertically with reference to the upper end s of the discharge-passages g g. On the top of the valve-stem is a button or head, l, so arranged that, when a flat-iron is placed on the stand A, such flat-iron shall rest on the head of the valve-stem, and force downward the said stem, so as to open the valve and allow gas to flow from the chamber b into the chamber f. The valve-seat c, and its valve d, or either, should be made so as to enable it to leak from the chamber b, through the valve opening, a sufficient amount of gas to keep a slight flame in existence on the discharge-mouths of the passages g, such flame serving to put in combustion the larger amount of gas which would escape from the chamber b, when the valve thereof is opened by the pressure of the flat-iron on its stem.

When the apparatus is in use, air will enter each of the chambers g by its hole h, and will mingle with the gas passing through such chamber g, and be burned therewith, the whole producing a blue flame of great heating power. On removing from the stand A the flat-iron or article to be heated, the spring will elevate the valve, so as to greatly diminish the passage of gas through the burner. Below the adjustable deflector is a conical flame-guide, p, which, with the deflector, serves to spread the flame when the deflector is screwed down toward such guide. The whole forms a very efficient and convenient apparatus for heating a flat-iron or a kettle.

I claim the combination as well as the arrangement of the valve d and its stem e with the flat-iron stand A and the gas-burner B, applied thereto substantially as specified.

I also claim the combination and arrangement of the adjustable deflector k with the valve d, its stem e, the flat-iron stand, and the burner, arranged as set forth.

I also claim the combination and arrangement of the conical flame-guide p with the adjustable deflector k, the valve d, its stem e, and the burner B, or the latter and the flat-iron stand A, arranged as represented.

Witnesses:

R. H. EDDY,

F. P. HALE, Jr.

ALBERT HALLOWELL.
